METHOD OF WORKING UP LOW VALUED MATERIALS SUCH AS PITCH, ACID SLUDGE, AND THE LIKE

Alfred Reis, Berlin-Lichterfelde, Germany, assignor to Pape & Co., G. m. b. H., Rahilstedt, Germany, a corporation

Application February 10, 1933, Serial No. 656,204
In Germany February 16, 1932

9 Claims. (Cl. 196—148)

This invention relates to processes for working-up pitch, tar, acid sludge and other combustible substances by heat treatment with the exclusion of air, for the purpose, in particular, of producing liquid fuels. The process differs essentially on the one hand from coking processes which produce coke in coherent form, and on the other hand from cracking processes in which the avoidance of the formation of appreciable amounts of solid coke-like residues is important if the process is to be of technical or commercial value.

The process in accordance with the invention may be employed for example for working-up acid pitches or acid sludges of all kinds which are accumulated in the refining of petroleum and like products and are not only worthless but extremely troublesome. It is possible by means of the invention to obtain from these materials light liquid hydrocarbons, that is to say a valuable product.

The process is also suitable in particular for working-up inferior heavy oils and bituminous substances and similar products which remain over from the treatment of petroleum or coal.

The hydrocarbons obtained by the process in accordance with the invention represent especially readily volatile, gasoline-like fuels of high quality which exhibit no tendency to knock.

A process for working-up acid sludges is known in which the organic sulphur compounds are decomposed by the action of air at an elevated temperature and the whole of the sulphur is converted into sulphur dioxide and sulphur trioxide. The main object of this process is to work-up the gas mixture obtained for the manufacture of sulphuric acid. The organic material is mostly converted into coke and only a moderate proportion can be obtained in the form of liquid hydrocarbons. The quality of the hydrocarbons produced is necessarily inferior under these circumstances. A process for working-up acid sludges is also known according to which these are carefully and gradually heated in stages in order to prevent scum or foaming.

In contradistinction to these known processes the essential feature of the process according to the invention is that the material to be treated, for example the acid sludge, is introduced into a retort heated to red heat and is heated with the exclusion of air and gasified. For this purpose a temperature of about 700 to 800° C. has proved to be suitable.

The single figure of the drawing is a diagrammatic elevation of the invention, portions of the apparatus being broken away.

In this drawing the reference numeral 2 indicates a sheet metal container into which the acid sludge or other material to be treated is placed. This container is heated by suitable heating

means such as by the burner 4. From this container 2 the material flows to a mixer or mill 6 after which it flows to a container 8. The material is pumped from the container 8 by the pump 10 through the pipe 12 to the dust separator 14, which is filled with Raschig-rings 16.

The gases evolved in the retort 18 simultaneously enter the separator 14 from below through the opening 20. These gases pass upwardly through the separator 14 as the liquid material 10 flows downwardly therethrough. The liquid material together with solid particles it has picked up from the gases pass from the separator 14 to the mill 6 and back to the container 8. The material is also drained off by the pump 22 from this container and forced through the pipe 24 to the atomizer nozzle 26 at the top of the retort 18.

The retort 18 is enclosed by masonry 28 and is heated, for example, by oil burners 30. Through the conduit 32 a suitable gas may be injected by means of which the material is atomized in the nozzle 26.

The atomized material passes downwardly through the retort and is gasified and evaporated therein. The retort is provided with scrapers 34 which extend from top to bottom. They are rotated by means of a shaft 36 and a pinion gear 38 which engages gear teeth on the inner circumference on the annular ring 35 to which the scrapers are attached. The outer circumference of the ring 35 is provided with a peripheral groove 37 which is engaged by an annular ring 39 secured to the wall of the retort 18. This ring 39 supports the scraper assembly and permits the same to rotate when driven by the pinion gear 38.

The larger solid particles of the material fall down into a worm conveyor 40 which conveys away these particles, which are chiefly coke. The gases and vapors which are formed pass through the opening 42 to a centrifugal separator 44 which separates the finer solid particles and collects them in a worm conveyor 46. The gases finally pass through the pipe 48 to the dust separator 14 where they are cleaned again and from the dust separator they pass through the pipe 50 to a cooling apparatus (not shown).

The vapors and gases may be passed to a cracking chamber 52 as will be hereinafter described.

On introducing the starting material into the red hot retort the greater part is converted by the action of rapid heating, in particular by the radiation of heat from the wall of the retort, into vaporized hydrocarbons and besides ashes only a little coke-like residue is produced. A considerable part of the hydrocarbon vapors given off can be obtained by fractionation in the form of valuable fuels, the physical and chemical properties of which resemble those of a good gasoline obtained by a cracking process.

The process is based, as has been emphasized

above, on the employment of an unusually rapid heating of the raw material in a gasifying chamber of which the walls are heated to a high temperature and act mainly by radiation on the raw material. In order to increase the area of the radiating surface and to reduce the thickness of the layers through which the radiation passes the gasifying chamber may be provided with built-in parts or insertions which must also be heated 10 to a high temperature.

With the rapid heating there are necessarily associated the features that the amount of material present in the gasifying chamber is kept small and the duration of the material in the 15 chamber is short. It has been found that by suitably regulating the operating conditions any material can be gasified in a very short time in such a manner that only a dry solid residue remains over.

20 A particularly suitable method of carrying the process according to the invention into effect is to introduce the material into the gasifying chamber in a finely divided form which may be effected in particular by atomizing or disintegrating the 25 liquid or liquefied material through nozzles or by other known means for this purpose.

In the process according to the invention the size of the drops, the intensity of the radiation and the duration in the gasifying chamber must 30 be relatively regulated or adapted to suit one another in such a manner that the residual grains leave the gasifying chamber in a condition in which they have been sufficiently used up. The 35 period of duration in the gasifying chamber and the passage of the drops through it can also be regulated by the introduction of gases which exert no harmful effect on the gasified material.

It is also important that the drops in the 40 middle of the retort, that is to say those lying furthest away from the radiating surface, are subjected to a sufficiently intense radiation. The density of the drops, therefore, must not be so great that the radiation is too strongly absorbed before it 45 reaches the middle of the retort; on the other hand, the economy of the process requires that the permissible density of the drops and, therefore, the permissible output of the gasifying chamber is sufficiently utilized. This taking into 50 consideration of the absorption of the radiation in the gasifying chamber which is filled with drops is, therefore, a feature of the process.

Example 1

55 As the gasifying retort there is employed a vertical iron tube of 40 cm. internal width and 3 metres in height. Into the retort, which is heated to 750° C., molten petrol-pitch is blown-in from the top through an atomizing nozzle, the output 60 being 60 kg. per hour. The size of the drops is of the order of 0.1 mm., the period of duration in the gasifying chamber is of the order of 1 second. The pressure in the retort is the atmospheric pressure. For regulating the atomization and 65 the movement of the material in the gasifying chamber the gases resulting from the decomposition of the material are employed.

An important advantage of the process is that the vapors formed in the gasifying chamber may 70 be conducted to a following heat treatment process (cracking) of any desired nature without previous condensation, and that for this cracking process the temperature, the duration of the process and the form of the cracking chamber 75 may be entirely independent of the gasifying condi-

tions. Since the most favourable conditions for the gasifying process and the cracking are in general considerably different, the division of the heat treatment into two parts enables the operation to proceed more advantageously than when 5 the same conditions are maintained during the entire heating. According to the conditions, the gasifying chamber and the cracking chamber can be fitted in two separate furnaces or in one furnace. 10

It is advantageous in many cases to separate the residual grains formed in the gasifying chamber before introduction of the gas or vapor formed into the cracking chamber. Any suitable known apparatus may be employed for this separation 15 and the removal may take place continuously or intermittently. In general it is preferable to separate the residual grains dry, that is to say to maintain the separator at so high a temperature that the tar vapors cannot condense. The carbonaceous material which remains as residue and forms a valuable by-product in the case of a small ash content. 20

The process may be carried out at the ordinary pressure or at an increased pressure. The materials obtained, insofar as they cannot otherwise be profitably used, can be returned to the process. This holds good, in contradistinction to the usual cracking process, in particular also for heavy oils and for tar-like or pitch-like distillates. 30 In the case of raw materials which cannot be converted by heat alone without difficulty into a liquid which will flow, the admixture of distillates may also assist in facilitating the disintegration. 35

For the purpose of receiving or for receiving and removing the residue there may be arranged in accordance with the invention separate receptacles and continuously or intermittently acting apparatus for removing the residual grains. 40 For this purpose many kinds of apparatus which are well known per se are available.

In order to eliminate almost completely the evolution of sulphurous acids during decomposition of acid pitches or acid sludge in the red hot retort, the acid sludge, in accordance also with the invention is intimately mixed before the heat treatment with an excess of basic substances in the presence of water, and the mixture is treated 50 at the temperature of boiling water or at a somewhat lower temperature until the evolution of gas (sulphurous acid and carbonic acid) is ended. By this means it is possible to allow the gases evolved to escape in a uniform flow without the 55 formation of troublesome scum or foam.

Although during the neutralization process an emulsion-like mixture of water and sludge tends to occur, the excess water can subsequently be separated mechanically from the neutralized 60 mixture, so that the neutralized acid sludge can be conducted for further treatment into the highly heated retort in a condition in which it is nearly free from water. As basic additions there may be employed, for example, slaked lime, chalk, dolomite, magnesia, sodium carbonate. 65

Example 2

10 kg. of chalk are stirred with 20 litres of hot water and 20 kg. of acid sludge (originating from 70 the refining of lubricating oil) are gradually added with continuous stirring. After the vigorous development of gas has subsided stirring is continued at an elevated temperature until the evolution of gas is completed. After cooling the 75

excess water is poured off and the neutralized acid sludge is freed from the rest of the water by pressing.

In some circumstances it is advantageous to mix the neutralized acid sludge with other materials capable of being cracked before introduction into the retort because the yields of valuable hydrocarbons are then higher than with separate treatment. Further, by intimate mixture of the neutralized sludge with a sufficient quantity of oil the result can be obtained that there is formed a liquid, easily flowing emulsion which, like other liquids, can be pumped through pipes or sprayed through nozzles. For this purpose there may be employed suitable heavy oils and in particular the heavy oils which collect in the receivers in the treatment of acid sludges.

Example 3

20 Neutralized acid sludge is stirred with heavy oil and heated. The proportions of the mixture are 120 kg. of oil to 100 kg. of the crude acid sludge contained in the neutralized product. There is formed an emulsion which is stable at 25 90° C. and flows easily.

With the process in accordance with the invention the whole of the sulphur content of the acid sludge remains in the retort residue and is thus rendered harmless, with the single exception of 30 a proportion of sulphuretted hydrogen in the gas evolved, which can be absorbed in gas purifiers by known methods after condensation of the liquid fuel.

I claim:—

35 1. A method of working-up low valued materials such as pitch, acid sludge and the like to produce light liquid hydrocarbons therefrom, which comprises gasifying and evaporating a portion of said materials by rapidly passing the same in a finely divided state downwardly through a zone heated by radiation to a temperature equivalent to red heat and at least to about 700° C., and in which air has been excluded.

40 2. A method of working-up low valued materials such as pitch, acid sludge and the like to produce light liquid hydrocarbons therefrom, which comprises gasifying and evaporating a portion of said materials by rapidly passing the same in a finely divided state downwardly through a zone heated by radiation to a temperature equivalent to red heat and at least to about 700° C., and in which air has been excluded, and in then cracking the vapor thus formed.

45 3. A method of working-up low valued materials such as pitch, acid sludge and the like to produce light liquid hydrocarbons therefrom, which comprises gasifying and evaporating a portion of said materials by rapidly passing the same in a finely divided state downwardly through a zone heated by radiation to a temperature equivalent to red heat and at least to about 700° C., and in which air has been excluded, separating the solid particles from the vapor formed, and subjecting the vapor without being condensed to 50 a cracking process.

55 4. A method of working-up low valued materials such as pitch, acid sludge and the like to produce light liquid hydrocarbons therefrom, which comprises mixing said material with heavy oil, rapidly passing a portion of the mixed materials in a finely divided state downwardly

through a zone heated by radiation to a temperature over 700° C. and from which oxygen has been excluded, and cracking the vapor thus formed.

5 5. A method of working-up low valued materials such as pitch, acid sludge and the like to produce light liquid hydrocarbons therefrom, which comprises gasifying and evaporating a portion of said materials by rapidly passing the same in a finely divided state downwardly through a zone heated by radiation to a temperature equivalent to red heat and at least to about 700° C., and in which air has been excluded, regulating the duration of the passage of the divided material through said zone by introducing into 10 said zone a gas which does not affect the properties of the material and which by its own velocity regulates the passage of the material.

10 6. A method of working-up low valued materials such as pitch, acid sludge and the like to produce light liquid hydrocarbons therefrom, which comprises gasifying and evaporating a portion of said materials by rapidly passing the same in a finely divided state downwardly through a zone heated by radiation to a temperature equivalent to red heat, and in which air has been excluded, regulating the duration of the passage of the divided material through said zone by introducing into 15 said zone a gas which does not affect the properties of the materials and which by its own velocity regulates the passage of the material, subjecting the vapor formed without being first condensed to a cracking process.

20 7. A method of working-up low valued materials such as pitch, acid sludge and the like to produce light liquid hydrocarbons therefrom, which comprises mixing the material with water and a basic alkaline substance such as chalk to neutralize said material, rapidly passing said neutralized material in a finely divided state 25 downwardly through a zone heated by radiation to a temperature equivalent to red heat and at least to about 700° C. to gasify and evaporate the same, and cracking the vapor thus formed.

25 8. A method of working-up low valued materials such as pitch, acid sludge and the like to produce light liquid hydrocarbons therefrom, which comprises mixing the material with water and a basic alkaline substance such as chalk to neutralize said material, removing the excess 30 water from said neutralized material, mixing the neutralized material with oil, rapidly passing said mixture in a finely divided state downwardly through a zone heated by radiation to a temperature equivalent to red heat to gasify and 35 evaporate the same.

30 9. A method of working-up low valued materials such as pitch, acid sludge and the like to produce light liquid hydrocarbons therefrom, which comprises mixing the material with water and a basic alkaline substance such as chalk to neutralize said material, removing the excess 40 water from said neutralized material, mixing the neutralized material with oil, rapidly passing said mixture in a finely divided state downwardly 45 through a zone heated by radiation to a temperature equivalent to red heat to gasify and evaporate the same, and cracking the vapor thus formed.
